US0D1015139S

(12) **United States Design Patent** (10) **Patent No.:** **US D1,015,139 S**
(45) **Date of Patent:** **** Feb. 20, 2024**

(54) **PACKAGE**

- (71) Applicant: **Janssen Pharmaceutica NV**, Beerse (BE)
- (72) Inventors: **Michael Cannamela**, Atlantic Highland, NJ (US); **Emma Hubert**, San Jose, CA (US)
- (73) Assignee: **Janssen Pharmaceutica NV**, Beerse (BE)
- (**) Term: **15 Years**
- (21) Appl. No.: **29/872,262**
- (22) Filed: **Mar. 9, 2023**

Related U.S. Application Data

- (62) Division of application No. 29/717,663, filed on Dec. 18, 2019, now Pat. No. Des. 985,384.

(57) **CLAIM**

The ornamental design for a package, as shown and described.

DESCRIPTION

FIG. 1 is a perspective view of another embodiment of a new design of a package shown with a drug delivery device disposed therein;

FIG. 2 is a perspective view of the package of FIG. 1 shown with a lid removed;

FIG. 3 is a top view of the package of FIG. 1;

FIG. 4 is a top view of the package of FIG. 1 with the drug delivery device removed;

FIG. 5 is a bottom view of the package of FIG. 1;

FIG. 6 is a left view of the package of FIG. 1;

FIG. 7 is a right view of the package of FIG. 1;

FIG. 8 is a front view of the package of FIG. 1;

FIG. 9 is a back view of the package of FIG. 1; and,

FIG. 10 is an exploded view of the package of FIG. 1.

In the drawings, the broken lines are for the purpose of illustrating portions of the package that form no part of the claimed design.

1 Claim, 6 Drawing Sheets
